(57) **CLAIM**

The ornamental design for a bi-fold wallet, as shown and described.

DESCRIPTION

FIG. 1 is a perspective view of an open configuration of a bi-fold wallet, showing my new design;

FIG. 2 is a front elevation view thereof;

FIG. 3 is a first side elevation view thereof;

FIG. 4 is a second side elevation view thereof;

FIG. 5 is a rear elevation view thereof;

FIG. 6 is a perspective view of a closed configuration of the bi-fold wallet of FIG. 1;

FIG. 7 is a top plan view thereof;

FIG. 8 is a bottom plan view thereof;

FIG. 9 is a first side elevation view thereof;

FIG. 10 is a front elevation view of thereof, with the rear elevation view being a mirror image thereof; and,

FIG. 11 is a second side elevation view thereof.

The dashed lines represent stitching and are part of the claimed design.

1 Claim, 7 Drawing Sheets
